COMBINED SPROCKET AND CHAIN GUARD ASSEMBLY FOR A BICYCLE

William L. Manofsky and Dennis C. Patterson, Nashville, Tenn., assignors to The Murray Ohio Manufacturing Co., Brentwood, Tenn.

Filed Sept. 25, 1975, Ser. No. 616,817

Term of patent 14 years

Int. Cl. D12—11

U.S. Cl. D12—123

Zig. 1.

Fig. 5.

Fig. 7.

Fig. 6.

Fig. 8

*Fig. 10.**Fig. 9.*FIG. 1 is an exploded perspective view of a combined sprocket and chain guard assembly for a bicycle showing our new design;

FIG. 2 is a front elevational view thereof;

FIG. 3 is a rear elevational view thereof;

FIG. 4 is a side elevational view thereof;

FIG. 5 is an exploded perspective view of a second embodiment of a combined sprocket and chain guard assembly for a bicycle showing our new design;

FIG. 6 is a front elevational view of FIG. 5;

FIG. 7 is a rear elevational view of FIG. 5;

FIG. 8 is an exploded perspective view of a third embodiment of a combined sprocket and chain guard assembly for a bicycle showing our new design;

FIG. 9 is a front elevational view of FIG. 8; and FIG. 10 is a rear elevational view of FIG. 8.

We claim:

The ornamental design for a combined sprocket and chain guard assembly for a bicycle, substantially as shown and described.
